HOMER A. CHENEY AND ELMER R. CHENEY, OF MILLERSBURG, IOWA.

GATE.

SPECIFICATION forming part of Letters Patent No. 636,895, dated November 14, 1899.

Application filed June 26, 1899. Serial No. 721,881. (No model.)

To all whom it may concern:

Be it known that we, HOMER A. CHENEY and ELMER R. CHENEY, citizens of the United States, residing at Millersburg, in the county 5 of Iowa and State of Iowa, have invented a new and useful Gate, of which the following is a specification.

The invention relates to improvements in gates.

10 The object of the present invention is to improve the construction of swinging gates, more especially the means for opening and closing the same, and to provide a simple, inexpensive, and efficient one adapted to be operated at a distance from either side of it and capable of being readily opened and closed in high winds.

15 A further object of the invention is to provide a gate of this character which will not drag upon the ground as it is opened and closed and which will be adapted to clear such obstructions as snow.

20 The invention consists in the construction and novel combination and arrangement of 25 parts hereinafter fully described, illustrated in the accompanying drawings, and pointed out in the claims hereto appended.

25 In the drawings, Figure 1 is a perspective view of a gate constructed in accordance with 30 this invention. Fig. 2 is a detail sectional view illustrating the manner of hinging the gate.

35 Like numerals of reference designate corresponding parts in both figures of the drawings. 1 designates a swinging gate, preferably 40 consisting of a rectangular frame and a body portion of woven wire, which is adapted to permit the wind to pass through it readily and which facilitates the operation of the 45 gate in high winds. The gate is provided with upper and lower eyes 2 and 3 and is mounted on a vertical shaft 4, which is provided at its top with an L-shaped arm 5, extending into the upper eye 2 of the gate, 45 and forming an upper pintle, the upper eye being shorter than the lower eye, which projects rearward from the bottom of the gate. The lower eye receives the vertical shaft, which is preferably constructed of tubular 50 metal and which is supported upon an L-shaped bolt 6, having one arm threaded into a hinge-post 7 and its other arm extending

vertically into the lower end of the tubular shaft. The upper end of the shaft is journaled in a suitable bearing, preferably consisting of a block or arm 8, projecting from the top of the post toward the gate and provided with an opening. The L-shaped arm, which forms the upper pintle, is arranged to clear the block 8, and the upper portion of the 60 shaft and the arm 5 may consist of a casting, as clearly shown in Fig. 2 of the accompanying drawings. The casting is provided with a depending socket to receive the upper end of the tube or pipe of which the body portion 65 of the shaft is constructed, and the said socket 9 is preferably threaded, as shown in Fig. 2; but any other means may be employed for securing the casting to the tube.

When the shaft is rotated by the means 70 hereinafter described, the upper arm 5 tilts the gate upward and rearward, raising the front end, releasing a latch 10 and causing the gate to swing by gravity to open or close it, and this prevents the gate from dragging 75 upon the ground, and it also enables the same to clear deep snows and similar obstructions. The shaft is actuated by a rearwardly-extending lever 11, consisting, preferably, of a wooden bar and a casting 12, having inner 80 and outer portions arranged at an angle. The casting, which is provided with longitudinal flanges 13, has its outer portion arranged horizontally and provided with perforations receiving the upper end of the shaft 85 and the arm of the same, and these parts, which are rounded, as shown in Fig. 2, are secured to the casting by means of keys 14 or other suitable fastening devices.

90 The rear end of the lever is connected by an eyebolt 16 or other suitable fastening device with operating-ropes 17, extending from the gate in opposite directions and having their outer faces supported by guide-pulleys 18 and 19, mounted on uprights 20 and on 95 arms 21, extending therefrom. The arms 21, which are arranged at an inclination, are supported by rods, but any other suitable support may be provided for the outer portions of the operating-ropes. The guide-pulleys are preferably arranged in blocks, as shown in the accompanying drawings, and when either operating-rope is pulled upon the rear end of the operating-lever is drawn toward the oper- 100

ator and the gate swings in the opposite direction, and is thereby prevented from striking a team or frightening the same or stock. When the gate is open and the lever is in alignment 5 with the operating-ropes, the one which is to be operated to close the gate is offset from the lever by one of a pair of arms 22, mounted on the lever near the rear end thereof. The arms are arranged at an inclination, as clearly 10 shown in Fig. 1, and they are provided at their outer ends with forks 23, arranged to receive the operating-ropes.

The latch 10 consists of a hinged or pivoted bar arranged at the front end of the gate and 15 having its lower end secured to the same by a staple 24, which forms a pivot, and its upper end is arranged within a keeper or link 25, disposed at an inclination and limiting the outward movement of the latch. This 20 link or loop 25, which may consist of a staple, is fixed to the gate, and a spring 26 is interposed between the hinged bar and the gate and is adapted to hold the latter at the outward limit of its movement. The latch is 25 adapted to engage a double keeper 28 of a latch-post 29 when the gate is closed, and keepers or catches 30 are mounted on the uprights 20 for supporting the gate in its open position.

30 The invention has the following advantages: The gate, which is simple and comparatively inexpensive in construction, is positive and reliable in operation and is adapted to be readily opened and closed, and its front end 35 is lifted when it is operated, whereby it is adapted to swing clear of snow and other obstructions and is prevented from dragging on the ground. By lifting the gate in this manner it is caused to swing by gravity, and it is 40 thereby adapted to be readily operated in high winds. When the gate is closed, it is securely

fastened and cannot be accidentally opened by stock.

Changes in the form, proportion, size, and the minor details of construction within the 45 scope of the appended claims may be resorted to without departing from the spirit or sacrificing any of the advantages of this invention.

What is claimed is—

1. The combination of a shaft provided at 50 its upper end with an L-shaped arm, a gate hinged to the shaft and to the arm thereof, a lever provided with openings receiving the upper terminal of the shaft and the upper end of the arm, and operating mechanism connected with the lever, substantially as described. 55

2. The combination of a shaft provided at its upper end with an L-shaped arm, a gate hinged to the shaft and to the arm thereof, a lever secured to the shaft and to the arm thereof, and provided with laterally-disposed arms, and flexible operating connections attached to the lever and adapted to be engaged by the arms thereof, substantially as described. 60 65

3. The combination of a shaft provided at its upper end with a casting forming an L-shaped arm, a gate hinged to the arm and to the shaft, a lever secured to said casting, composed of a bar and a casting, one portion of 70 which is at an angle to the bar, and operating mechanism connected with the lever, substantially as described.

In testimony that we claim the foregoing as our own we have hereto affixed our signatures 75 in the presence of two witnesses.

HOMER A. CHENEY.
ELMER R. CHENEY.
